UNITED STATES PATENT OFFICE.

WILLIAM D. WILCOX, OF CHICAGO, ILLINOIS.

APPARATUS FOR MAKING GAS.

1,386,825.

Specification of Letters Patent.

Patented Aug. 9, 1921.

Application filed February 23, 1918. Serial No. 218,799.

To all whom it may concern:

Be it known that I, WILLIAM D. WILCOX, a citizen of the United States, and a resident of Chicago, in the county of Cook and State of Illinois, have invented a certain new and Improved Apparatus for Making Gas, of which the following is a specification, reference being had to the accompanying drawings.

10 My invention relates to the manufacture of gas for domestic and other uses, and has to do particularly with the manufacture of a combined coal and water-gas. The object of my invention is to provide a new and improved apparatus, by which gas suitable for domestic and other uses may be produced, and which will be well adapted for comparatively small installations as well as for those of greater capacity. My improved apparatus provides for the utilization of the blast gases produced during the blast period of water-gas production in the extraneous heating of coal in a separate coking chamber, and at the same time passing 25 the water-gas through such coal, thereby economically producing a combined coal and water-gas. It also utilizes the sensible heat of such blast gases in the production of steam to be used during the subsequent run 30 period, thereby further conserving the heat derived from the combustion of the blast gases. In its best embodiment my improved apparatus provides for the production of water-gas simultaneously with the combustion 35 of the blast gases and the incidental extraneous heating of the coal in the coking chamber by the combustion of the blast gases and the direct heating of such coal by the passage therethrough of the hot water-gas, thus securing the greatest economy of 40 heat and time, together with a continuous production of the combined coal and water-gas.

In the accompanying drawings, 45 Figure 1 is an end elevation, showing the generators and the lower portion of the coking chamber;

Fig. 2 is a partial horizontal section on line 2-2 of Fig. 5;

50 Fig. 3 is a longitudinal vertical section substantially on line 3-3 of Fig. 4;

Fig. 4 is a horizontal section on line 4-4 of Fig. 3;

55 Fig. 5 is a vertical cross-section on line 5-5 of Fig. 3, and

Fig. 6 is a vertical cross-section on line 6-6 of Fig. 3.

Referring to the drawings,

7-8 indicate the side walls of the apparatus and 9-10 the end walls thereof. 60 11-12 indicate two similar vertical generating chambers which are provided at one end of the apparatus, and are separated by a partition wall 13, as shown in Figs. 4 and 6. Said generating chambers are provided 65 near their lower ends with grates 14-15, below which are ash pits 16-17, as shown in Fig. 6. 18-19 indicate doors closing openings into said ash pits through which ashes may be removed, and 20-21 indicate 70 doors which close openings into said generators immediately over the grates 14-15 therein for the removal of clinkers, etc. 22-23 indicate openings at the upper ends of said generating chambers, through which 75 the fuel, such as coal or a mixture of coal and coke is introduced, said openings being closed by gas tight doors 24-25, as shown in Fig. 6.

26 indicates a boiler which is set between 80 the side walls 7-8 at the opposite end of the apparatus from the generating chambers 11-12, as shown in Figs. 3 and 4. 27 indicates a coking chamber placed between the generating chambers 11-12 and the boiler 85 26, as shown in Fig. 4, and 28-29 indicate two secondary combustion chambers, preferably in the form of checker-brick containing chambers also placed between the generating chambers 11-12 and the boiler 90 26, said checker-brick chambers being at opposite sides of the coking chamber 27, as illustrated in Fig. 4. 30 indicates a passage leading from the upper portion of the generating chamber 11 to the checker-brick 95 chamber 28, and 31 indicates a similar passage connecting the upper portion of the chamber 12 with the checker-brick chamber 29. 32 indicates a passage connecting the lower portion of the checker-brick chamber 28 with a chamber 33 below the boiler 100 26, and 34 indicates a similar passage connecting the lower portion of the checker-brick chamber 29 with the chamber 33. The passages 32-34 are indicated by dotted 105 lines in Fig. 4, and the passage 34 is shown in full lines in Fig. 3. These passages are provided, respectively, with valves 35-36 by means of which they may be opened and closed. The purpose of these valves is to 110

control the flow of gas from the checker-brick chambers 28-29 to the boiler 26, and any suitable form of valve by which that may be accomplished may be employed. In Fig. 4 I have shown hand-wheels 37-38 for operating said valves.

As best shown in Figs. 3 and 4, the checker-brick in the chambers 28-29 does not completely fill them, there being unoccupied spaces 39-40 at the ends of said chambers adjacent to the generating chambers, which spaces serve as distributing passages to permit the gases entering said chambers from the generating chambers to be distributed throughout the checker-brick chambers, respectively. Similarly, passages 41-42 are provided at the opposite ends of said checker-brick chambers to facilitate the flow of gases at those ends. 43-44 indicate steam pipes which connect with the lower portions of the passages 41-42, and are also connected with the boiler 26 so that steam from the boiler may be discharged into the ends of the checker-brick chambers 28-29 adjacent to the boiler. Said pipes are provided with valves 45-46 for controlling the admission of steam to the checker-brick chambers. 47-48 indicate passages leading from the ash pits 16-17, respectively, to the coking chamber, said passages being controlled by valves 49-50 shown in Figs. 3 and 6.

The construction of the coking chamber 27 is best shown in Figs. 4 and 5. It will be noted that the side walls of such chamber are inclined so that said chamber gradually increases in width from the top downward, thus facilitating the downward passage of the fuel. That portion of the coking chamber which lies between the checker-brick chambers 28-29 is provided with inner walls 51 of steel or any other suitable material backed with a comparatively thin brick wall 52, thus permitting the heat of the checker-brick chamber to be communicated to a certain extent to the fuel in the coking chamber. The steel inner lining 51 prevents leakage of gas through the brick portion of the dividing wall between the coking chamber and the checker-brick filled chambers on each side thereof. Said lining may readily be removed and replaced when necessary. The checker-brick chambers 28-29 lie above the passages 47-48 as shown in Fig. 5, and that portion of the coking chamber which lies below the passages 47-48, which portion I have designated by the numeral 27^a, is surrounded by a metal wall 53 which is in turn surrounded by a second metal wall 54 which forms therewith a chamber 55, the purpose of which will be hereinafter explained. 56 indicates a discharge elbow or chute at the lower end of the coking chamber which is closed by a swinging gate 57 having a latch 58 or other suitable means for holding it in

its closed position. 59 indicates a water pipe connected with the lower portion of the coking chamber, as shown in Fig. 5. 60 indicates an air pipe which connects with the lower portion of the chamber 55, and is adapted to receive air from a pump 61 of any suitable description. 62 indicates a pipe leading from the upper portion of the chamber 55, at the side opposite that with which the pipe 60 connects, to a vertical pipe 63 shown in Figs. 1 and 3, which is mounted at the end of the apparatus adjacent to the generating chambers 11-12, and preferably lies midway between said chambers, as shown in Fig. 1. Branch pipes 64-65 controlled by valves 66-67, respectively, lead from the pipe 63 to the lower portions of the generating chambers 11-12, respectively, below the grates therein, as shown in Fig. 3. Similar branch pipes 68-69 controlled by valves 70-71, respectively, lead from the upper end of the pipe 63 to the upper portions of the generating chambers 11-12, respectively, as shown in Figs. 1 and 4.

72 indicates a gas pipe which leads from the upper portion of the coking chamber 27 to a receiving tank or hydraulic seal pot 73 which may be placed in any suitable location, but for convenience of description is here illustrated as being above one of the checker-brick chambers. The tank 73 is adapted to contain water, as shown in Fig. 5, and is provided with an overflow pipe 74. 75 indicates a gas outlet pipe leading from the upper portion of the tank 73. 76 indicates a coal reservoir for facilitating the introduction of fuel into the upper portion of the coking chamber 26, said reservoir having a gas tight cover 77. 78-79 indicate man-hole covers which cover man-holes through which access may be had from above to the checker-brick chambers.

It will be noted that the apparatus described comprises two similar generators each having its own checker-brick chamber, and a single coking chamber arranged to operate with said generators. In practice the "blast" and "run" periods of the two generators alternate so that the continuous production of gas is provided for, the operation being as follows: When the generator 12 is on blast and the generator 11 on run, the valve 50 which controls the passage 48 which leads from the ash pit of generator 12 to the coking chamber, is closed and the corresponding valve of the generator 11 is open; also the valve 36 in the passage 34 leading from the checker-brick chamber 29 to the space below the boiler is open and the corresponding valve 35 is closed. The valve 46 in the steam pipe 44 is also closed and the corresponding valve 45 in the steam pipe 43 is open. At this time the valve 67 which controls the admission of primary air

through pipe 65 to the generator 12 below the gate-bars therein, and the valve 71 controlling the admission of secondary air through pipe 69 to the upper portion of said generator, are open and the corresponding valves 66—70 are closed. The pump 61 is also in operation to force air under pressure through the chamber 55 at the lower end of the coking chamber, and thence through pipe 62 to the air pipe 63. Bearing these conditions in mind, it will be apparent that primary air entering ash pit 17 will rise through the grate-bars 15 and will pass up through the fuel in the generator 12. Owing to the fact that the air so supplied to the generator 12 comes from the chamber 55 surrounding the lower end of the coking chamber it will be hot. The upward passage of the primary air through the fuel in the generator 12 promotes combustion of such fuel, the gases liberated rising to the upper part of said generator where they become intermixed with secondary air which insures their complete combustion. The burning gases pass from the upper portion of the generating chamber 12 through the passage 31 into the space 40 of checker-brick chamber 29, from which space they are distributed to the spaces between the checker-brick in said chamber until ultimately they reach the space 42 at the opposite end of said checker-brick chamber, and thence pass out through passage 34 into the space below the boiler 26. During their passage through the checker-brick chamber, they highly heat the checker-brick therein, giving up thereto a considerable part of their heat, but when they reach the boiler they are still hot enough to heat the water therein to a high temperature, forming steam. After passing through the boiler, the gases escape through a suitable outlet, such as a stack 80 shown in Fig. 3.

During the same period of time the generator 11 may be operating on run as above suggested, in which case steam from the boiler is admitted through pipe 43 to the space 41 of checker-brick chamber 28, the checker-brick of which will have been heated to a high temperature during the previous blast period of the generator 11. Consequently, the steam becomes highly superheated by its contact with the hot checker-brick, and in that condition enters the upper end of the generator 11 through passage 30. It then passes down through the body of incandescent fuel in said generator, by the heat of which it is decomposed with the formation of hydrogen and carbon monoxid. The water-gas thus produced passes into the ash pit 17 and through passage 47 into an intermediate zone of the coking chamber. For the purpose of laterally distributing the water-gas entering the coking chamber so that it will rise uniformly

through the coal therein, the passages 47—48 are extended along the sides of the coking chamber and open laterally thereinto, as shown in Fig. 5. The gases under the pressure of formation, backed up by the steam pressure behind them, rise through the coal in the coking chamber, liberating the gases held by the coal, and the combined gases pass out through outlet pipe 72 to the well 73, and may be purified and subjected to such further treatment as may be desired. The liberation of the gases carried by the coal is promoted by heat disseminated through the walls of the upper portion of the coking chamber from the checker-brick chambers, and the downward movement of the coal in the coking chamber is promoted by the widening out of said walls, as has been explained. Coal is admitted from time to time from the fuel reservoir 76 into the upper portion of the coking chamber, and the finished coke is removed at intervals from the lower end of the coking chamber through the gate 57, in practice coal being admitted and coke being removed during alternating periods. During the downward passage of the coke in the lower portion 27^a of the coking chamber it gives up considerable part of its heat to the air which is caused to flow through the chamber 55 under the pressure of the fan or pump 61, so that such air is heated and the coke when discharged is materially cooled. The downward movement of the coke in the coking chamber is further aided by the inclined 100 sides of the coking chamber. The air heated in the chamber 55 as described, is conducted to the pipe 63 which supplies air to the primary and secondary air outlets of the generators, as has already been explained. 105

After each removal of coke, water is admitted to the lower end of the coking chamber through the pipe 59, which may be provided with a valve 81 for that purpose, a sufficient quantity of water being admitted 110 to provide a water seal to prevent any escape of gas through the gate 57. This water coming into contact with the coke in the lower portion of the coking chamber, quenches it, and is converted into steam 115 which passes up through the fuel body in the coking chamber under the pressure of its formation, resisting by its upward flow any downward passage of water-gas entering the coking chamber through either of 120 the passages 47—48. It also absorbs heat from the coke, which it may, in some degree, impart to the freshly charged coal in the upper part of the coking chamber, thus performing the function of transferring 125 heat upward in addition to the functions of preventing the escape of combustible gases through the gate 57, and quenching the coke, as has been described. During the time when coke is being removed from the 130

coking chamber, the valve 49 or 50 of the generator on run is closed, (the corresponding valve of the other generator is already closed during that period, as has been explained), and is allowed to remain closed until the water seal has been formed as above described. The steam formed by the quenching of the coke has enough pressure to overcome the gas being evolved in the upper portion of the coking chamber, and therefore, prevents the escape of gases from the upper portion of the coking chamber through the opening at the lower end thereof when the gate 57 is opened, thus avoiding the danger to the operator which would ensue if such gases were allowed to escape.

Upon the completion of the blast and run periods above described, the several valves are manipulated to reverse the operation of the generators and the direction of the flow of gases through the checker-brick chambers, the gases conducted to the coking chamber being then admitted thereto through the passage 48, the reactions which take place in the coking chamber continuing unchanged.

It will be noted that by the use of the apparatus described the following beneficial results, among others, are realized:

1. The coal charged into the coking chamber is coked and its volatiles distilled off in part by the heat produced by the secondary combustion of the blast gases passing inward through the walls which separate the coking chamber from the checker-brick chamber, and in part by the heat in the water-gas coming into direct contact with it. Both of these heats are in a great degree by-products or waste heat in the production of a straight water-gas.

2. The residue of heat in the blast gases is usefully employed in making the steam needed in the generators for the production of water-gas, and the steam passing as it does through the checker-brick chambers before entering the generators is highly superheated so that its decomposition and the formation of hydrogen and carbon mon-oxid takes place more quickly and with less draft upon the heat in the generator fuel. Moreover, a continuous supply of heat to the steam boiler is provided.

3. The checker-brick acts as a species of heat reservoir so that there is less variation in the temperature in the checker-brick chambers in the interval between blast and run periods than would otherwise be the case.

4. One or the other of the generators being substantially at all times producing water-gas, there is a continuous current of hot water-gas passing into the material in the coking chamber.

5. By frequent additions of fresh coal to

the upper part of the coking chamber, there is always relatively cold material at the top through which the water-gas must pass, thus extracting the largest possible proportion of its sensible heat before its discharge therefrom. 70

6. Each of the charges of coal introduced into the coking chamber passes down by gravity through said chamber as the residue is removed at the bottom, and consequently 75 each of such charges is subjected to the same conditions as regards heating as every other charge, thereby insuring a fairly uniform product.

7. The passage of the residue formed in 80 the coking chamber through the comparatively cool lower portion of said chamber serves to extract from it after it has been substantially coked a large part of its sensible heat, and with the cooling effect of the 85 turning into steam of the water admitted to the lower portion of the coking chamber and of the superheating of such steam by contact with the coke in passing upward, the residue in the bottom of the coking 90 chamber is quenched and cooled prior to its removal. The steam in the lower portion of the body of the coke prevents any downward passage of water-gas and its escape into the air when the lower end of the cok- 95 ing chamber is opened for the removal of coke, thereby avoiding danger to the operator.

8. The cooling of the coke through the action of the air circulating around the lower 100 portion of the coking chamber imparts its heat to such air, and in that way the heat is conserved and restored to the process, as the heated air is conducted to the generators and used to support combustion. To 105 the extent that it is preheated, it absorbs less of the heat of combustion in attaining the temperature necessary for combustion.

9. By grouping the several parts of the apparatus in the manner described, the 110 amount of heat lost through radiation is materially reduced, thereby economizing in the cost of operation.

In the use of the apparatus thus far described, it may occur that the coal in the coking chamber, and particularly that portion which occupies the space therein farthest removed from the heated walls thereof, will not be heated to the degree necessary or desired for the production of coke or 115 the fairly complete removal therefrom of its volatile elements, and my invention, therefore, contemplates the provision of means by which superheated water gas may be passed into the coking chamber, thereby raising 120 the temperature to which the fuel to be carbonized will be brought. For this purpose I provide steam pipes 82-83 which discharge into the ash pits 16-17 adjacent to the grate bars 14-15; said steam pipes 125 130

are supplied with steam from the boiler 26, or any other suitable source, and are provided with valves 84—85, respectively, by which the flow of steam therethrough may be controlled. 86—87 indicate gate valves in openings leading from the lower portions of the passages 41—42 to the passages 47—48, as shown in Figs. 3 and 5. It will be apparent that by closing the valves 49—50 and 10 opening the valves 86—87, steam admitted through the pipes 82—83 may be caused to flow upward through the generating chambers, thence through the checker brick chambers and down into the passages 47—48, 15 which as has been explained, discharge into the coking chamber 27. In practice, at the conclusion of the blast period of either generator, the gate valve 86 or 87, as the case may be, controlling the passage of the waste 20 gases from the appropriate checker brick chamber to the boiler would not be at once closed, but a short period of time would be allowed to elapse following the shutting off of the secondary air during which steam 25 would be admitted through the appropriate pipe 82 or 83 to the ash pit of that generator. The steam so admitted would rise through the fuel in the generator, with the 30 production of water gas, which would flow through the checker brick chamber, purging the fuel body of the combustion products and also the open space above the fuel and the checker brick chamber connected therewith. The appropriate gate valve 37 or 38 would 35 then be closed and the gate valve 86 or 87 opened, permitting the water gas, which would then be highly superheated by contact with the checker brick chamber, to escape into the passage 47 or 48 and thence into the fuel 40 in the coking chamber. In this mode of operation a larger proportion of the fuel in the generating chamber will be consumed in supplying heat to the checker brick chamber, the total volume of water gas per unit of 45 generator fuel will be less, but the total number of heat units passed into the coking chamber will be increased, and the fuel to be carbonized will be brought to a higher temperature, as stated above. If desired 50 also this mode of operation could be alternated with that previously described, making a down run through the generating chamber during one cycle and an up run during the succeeding cycle, a practice which 55 aids in preserving good conditions in the fuel bed therein.

The apparatus described may be modified in many respects without departing from the invention set forth in the generic 60 claims hereinafter made, and I wish it to be understood that my invention includes such changes or modifications as would occur to those skilled in the art.

What I claim as my invention, and desire 65 to secure by Letters Patent, is:—

1. A gas making apparatus comprising a generator, a secondary combustion chamber communicating with the upper portion of said generator, a separate coking chamber adjacent to said secondary combustion chamber and adapted to be heated therefrom, means for admitting steam into said secondary combustion chamber, a duct connecting the lower portion of said generator with said coking chamber, and controlling devices for 70 controlling the flow of gases through the apparatus, whereby blast gases from the generator may be caused to flow through said secondary combustion chamber, and gases formed in said secondary combustion chamber 80 may be caused to flow into the upper portion of the generator and thence downward through the material therein to said coking chamber.

2. A gas making apparatus comprising a generator, a secondary combustion chamber communicating with the upper portion of said generator, a separate coking chamber adjacent to said secondary combustion chamber and adapted to be heated therefrom, means for admitting steam into said secondary combustion chamber, a duct connecting the lower portion of said generator with said coking chamber, controlling devices for 90 controlling the flow of gases through the apparatus, whereby blast gases from the generator may be caused to flow through said secondary combustion chamber, and steam superheated in said secondary combustion chamber may be caused to 95 flow into the upper portion of the generator and thence downward through the material therein to said coking chamber, and means for admitting air into the upper portion of 100 said generator.

3. A gas making apparatus comprising a generator, a secondary combustion chamber communicating at one end portion thereof with the upper portion of said generator, a boiler connected with the opposite end portion of said secondary combustion chamber and heated by blast gases therefrom, a steam pipe leading from the boiler to the latter end portion of said secondary combustion chamber, and controlling devices for controlling 110 the flow of gases in one direction or the other, from said generator through said secondary combustion chamber, or vice versa.

4. A gas making apparatus comprising a generator, a secondary combustion chamber 120 communicating at one end portion thereof with the upper portion of said generator, a boiler connected with the opposite end portion of said secondary combustion chamber and heated by blast gases therefrom, a steam pipe leading from the boiler to the latter end portion of said secondary combustion chamber, controlling devices for controlling the flow of gases in one direction or the other, from said generator through said secondary 125 chamber, or vice versa.

combustion chamber, or vice versa, a coking chamber adjacent to and heated by said secondary combustion chamber, and means for conducting gases flowing from said secondary combustion chamber down through said generator to said coking chamber.

5. A gas making apparatus comprising a generator, a secondary combustion chamber communicating with the upper portion of
10 said generator, a coking chamber adjacent to said secondary combustion chamber and arranged to be heated therefrom, a duct connecting the lower portion of the generator with the coking chamber, means associated
15 with the coking chamber for heating air, means for supplying air heated by the coke in said coking chamber to said generator, and controlling devices for causing gases to flow from said generator through said secondary combustion chamber during certain periods, and during other periods to flow from said secondary combustion chamber down through said generator into said coking chamber.

25 6. A continuous gas producing apparatus comprising a plurality of generators, secondary combustion chambers communicating with the upper portions of said generators, a separate coking chamber connected
30 with the lower portions of said generators, means for admitting steam to said secondary combustion chambers, and controlling devices for controlling the flow of the gases, whereby gases may be caused to flow from
35 one of said generators through the secondary combustion chamber connected therewith and simultaneously steam may be caused to flow through the other secondary combustion chamber into the generator connected therewith and thence downward through said generator into said coking chamber, and vice versa.

7. A continuous gas producing apparatus comprising a plurality of generators, secondary combustion chambers communicating with the upper portions of said generators, a separate coking chamber associated with and heated by said secondary combustion chambers and connected with the lower portions of said generators, means for admitting steam to said secondary combustion chambers, and controlling devices for controlling the flow of the gases, whereby gases may be caused to flow from one of said generators through the secondary combustion chamber connected therewith and simultaneously steam may be caused to flow through the other secondary combustion chamber into the generator connected therewith and thence downward through said generator into said coking chamber, and vice versa.

8. A continuous gas producing apparatus comprising a plurality of generators, secondary combustion chambers communicating with the upper portions of said generators.

ators, a coking chamber connected with the lower portions of said generators, means for admitting steam to said secondary combustion chambers, controlling devices for controlling the flow of the gases, whereby gases 70 may be caused to flow from one of said generators through the checker-brick chamber connected therewith and simultaneously steam may be caused to flow through the other checker-brick chamber into the generator 75 connected therewith and thence downward through said generator into said coking chamber, and vice versa, and means for supplying said generators with air heated 80 by the coke in said coking chamber. 80

9. A gas making apparatus comprising a coking chamber having an opening at its lower end portion for the discharge of coke therefrom, an air chamber surrounding the lower portion of said coking chamber, a generator communicating with said coking chamber, means for causing gas to flow from said generator into said coking chamber, and means for conducting air from said air chamber into said generator. 90

10. A gas making apparatus comprising a coking chamber having an opening in its lower end portion for the discharge of coke therefrom, and a gas discharge outlet at its upper end portion, means for generating 95 water-gas, and a duct leading from said generating means and communicating intermediately with said coking chamber for introducing water-gas thereinto.

11. A gas making apparatus comprising a 100 coking chamber having an opening in its lower end portion for the discharge of coke therefrom, and a gas discharge outlet at its upper end portion, means for generating water-gas, a duct leading from said generating means and communicating intermediate with said coking chamber for introducing water-gas thereinto, and means for introducing water into the lower portion of 105 said coking chamber. 110

12. A gas making apparatus comprising a generator, a secondary combustion chamber communicating with the upper portion of said generator, a separate coking chamber adjacent to said secondary combustion chamber and arranged to be heated therefrom, means communicating with the lower portion of said generator for supplying steam thereto, a valve controlled passage between said secondary combustion chamber and the coking chamber for supplying the coking chamber with gases passing from the generator through said secondary combustion chamber, means for supplying steam directly to the secondary combustion chamber, whereby it may be caused to pass back therethrough to the generator, and valve controlled passages for conducting the gases formed in the latter operation to the coking chamber. 115 120 125 130

13. A gas making apparatus comprising a generator, a secondary combustion chamber, a separate coking chamber, and steam supply pipes and valve controlled passages, 5 combined and arranged so that steam may be introduced into the lower portion of the generator and caused to pass upward therethrough and through the secondary combustion chamber to the coking chamber, or, 10 alternatively, steam may be introduced into the secondary combustion chamber and caused to pass therethrough into the upper portion of the generator and down therethrough to the coking chamber.
14. An apparatus for the manufacture of gas comprising two water gas generators, two laterally placed secondary combustion chambers, an opening from the upper part 20 of each generator into the corresponding secondary combustion chamber, a vertical retort placed between the secondary combustion chambers, a closable opening from each secondary combustion chamber into the lower portion of the retort, means for supplying air to the upper and lower portions of each generator, and means for admitting steam to the lower portion of each generator.
15. An apparatus for the manufacture of gas comprising two water gas generators, 30 two laterally placed secondary combustion chambers, an opening from the upper part of each generator into the corresponding secondary combustion chamber, a vertical retort placed between the secondary combustion chambers, a closable outlet for waste gases from each secondary combustion chamber, means for admitting steam to each secondary combustion chamber, a closable opening from the lower portion of each generator into the lower portion of the vertical retort, and means for supplying air to the upper and lower portions of each generator.
16. An apparatus for the manufacture of gas comprising two water gas generators, 40 two adjacent secondary combustion chambers, an opening from the upper part of each generator into the corresponding secondary combustion chamber, a vertical retort placed between the combustion chambers, a closable outlet for waste gases in each secondary combustion chamber, closable openings from each secondary combustion chamber into the lower portion of the vertical retort, closable openings from the lower portion of each generator into the lower portion of the vertical retort, means for admitting steam to each secondary combustion chamber, means for admitting steam to the lower portion of each generator, and means for supplying air to the upper and lower portions of each generator.
17. An apparatus for the manufacture of gas comprising a plurality of water gas generators, a corresponding plurality of secondary combustion chambers, an opening 50 from the upper portion of each generator into the corresponding secondary combustion chamber, a vertical retort substantially inclosed by the secondary combustion chambers, a closable outlet for waste gases from each secondary combustion chamber, a closable opening from each secondary combustion chamber into the lower portion of the retort, means for supplying air to the upper and lower portions of each generator, 60 and means for admitting steam to the lower portion of each generator.
18. An apparatus for the manufacture of gas comprising a plurality of water gas generators, a corresponding plurality of secondary combustion chambers, an opening 65 from the upper portion of each generator into the corresponding secondary combustion chamber, a vertical retort substantially inclosed by the secondary combustion chambers, a closable outlet for waste gases from each secondary combustion chamber, means for admitting steam to each secondary combustion chamber, a closable opening from the lower portion of each generator into the lower portion of the vertical retort, and means for supplying air to the upper and lower portions of each generator.
19. An apparatus for the manufacture of gas comprising a plurality of water gas 80 generators, a corresponding plurality of secondary combustion chambers, an opening from the upper portion of each generator into the corresponding secondary combustion chamber, a vertical retort substantially inclosed by the secondary combustion chambers, a closable outlet for waste gases from each secondary combustion chamber, means for admitting steam to each secondary combustion chamber, a closable opening from the lower portion of each generator into the lower portion of the vertical retort, and means for supplying air to the upper and lower portions of each generator.
20. An apparatus for the manufacture of gas comprising a plurality of water gas 85 generators, a corresponding plurality of secondary combustion chambers, an opening from the upper portion of each generator into the corresponding secondary combustion chamber, a vertical retort substantially inclosed by the secondary combustion chambers, a closable outlet for waste gases from each secondary combustion chamber, means for admitting steam to each secondary combustion chamber, a closable opening from the lower portion of each generator into the lower portion of the vertical retort, and means for supplying air to the upper and lower portions of each generator.

WILLIAM D. WILCOX.
